Primary Examiner — T. Chase Nelson*Assistant Examiner* — Michelle E Wilson(74) Attorney, Agent, or Firm — Randall W. Fieldhack; David J. Arteman(57) CLAIM

We claim the ornamental design for the feminine pad with raised structure, as shown and described.

DESCRIPTION

FIG. 1 is a top perspective view of the body-facing surface of a feminine pad with raised structure.

FIG. 2 is a top view of the feminine pad of FIG. 1.

FIG. 3 is a first side view of the feminine pad of FIG. 1.

FIG. 4 is a second side view of the feminine pad of FIG. 1.

FIG. 5 is a first end view of the feminine pad of FIG. 1.

FIG. 6 is a second end view of the feminine pad of FIG. 1; and,

FIG. 7 is a back view of the feminine pad of FIG. 1.

The broken lines shown are for the purpose of illustrating environmental structure and form no part of the claimed design.
